10 Claims. (Cl. 216—62)

This invention relates to methods of uniting sheet materials to articles of work for various purposes, such as reenforcing, protecting, sealing, and the like, and to adhesively coated sheet materials adapted for these uses. While not limited thereto, the invention is especially concerned with the manufacture and sealing of cartons, boxes, and similar containers, and with reenforcing and sealing tapes adapted for use on such containers.

In the usual methods of making cartons, a carton blank is scored and folded and two side edges of the carton are brought into approximately abutting relationship where they later are secured together by a strip of reenforcing tape which is adhesively united to the margins adjacent to the abutting edges. This reenforcing operation is performed while the carton is in a flat or knocked down condition. In using the carton it is set up, filled, and closed by folding over the flaps in the proper order, and then is sealed by securing the carton flaps in their folded position by a sealing tape.

Both the sealing and reenforcing or stay tapes commonly used for these purposes are secured to the carton by a water soluble adhesive of some kind. If such cartons are subjected to a moist atmosphere for long periods of time, as for example, in ocean shipments through warm climates, the adhesives which unite the sealing and stay tapes to the carton are very likely to become softened to such an extent that they will let go.

This difficulty has long been recognized and many attempts have been made to overcome it.

For example, the reinforcing tapes have in some cases been secured by metallic fastenings to the carton, or have been dispensed with altogether and the sides of the carton secured together by metallic fastenings. Various kinds of "water-proof" or, more correctly, water-resistant adhesives have been used. For example, water glass is used to some extent in sealing cartons but is objectionable because of its extreme brittleness and the fact that it dries slowly. The most satisfactory of the water resistant adhesives for these purposes, considering the various requirements, including that of price, is asphalt, or a mixture in which asphalt is an important constituent. Tapes coated with such materials, while introduced some years ago, have never gone into use to

any substantial extent. These adhesives must be softened sufficiently by heat to bond them to the carton, and while tapes coated with them can readily be applied by hand methods, it is extremely difficult to apply them in taping or sealing machines at speeds satisfactory to the trade. In addition, the nature of these adhesives is such that it introduces serious practical difficulties in the handling and cutting of the tapes in taping and sealing machines. It is still, therefore, almost the universal practice to use water soluble adhesives in applying sealing and reinforcing or stay tapes to the cartons.

The present invention deals particularly with these considerations. It aims to improve the methods of applying sheet materials to articles of work with water resistant adhesives with a view to overcoming difficulties of the character above mentioned. It is a particular object of the invention so to improve these methods and materials as to permit the use of water resistant adhesive in the reenforcing and sealing of cartons at speeds comparable to those used in reenforcing and sealing cartons by existing methods.

The nature of the invention will be readily understood from the following description when read in connection with the accompanying drawing, and the novel features will be particularly pointed out in the appended claims.

In the drawing,

Figure 1 is a perspective view, somewhat diagrammatic, illustrating an apparatus with which steps of the method devised by this invention may conveniently be practiced;

Fig. 2 is a perspective view illustrating one way in which a carton may be reenforced and sealed;

Fig. 3 is a perspective view of a portion of a reenforcing or sealing tape embodying features of this invention;

Fig. 4 is a sectional view of another form of tape made in accordance with this invention; and

Fig. 5 is a cross-sectional view on a greatly enlarged scale illustrating a tape made in accordance with this invention.

According to the method of the present invention a temporary attachment of the sheet material to the carton or other article of work is first produced, and in connection with such attachment a water resistant adhesive is interposed

100

between said material and the work. Subsequently this material is fused or softened in any convenient manner sufficiently to bond the material securely to the carton.

5 In the reenforcing and sealing of cartons the method is most conveniently practiced with the aid of a novel tape disclosed in the parent application of which this case is a division. This tape comprises a backing strip 2, Fig. 3, of suitable sheet material, such as fabric, paper, or a combination of fabric and paper. One side of this tape is coated with a water resistant adhesive 3. This adhesive preferably is substantially devoid of tackiness at normal temperatures but is adapted to become tacky or sticky when heated to temperatures substantially above normal. It may consist of asphalt, or of a composition such as that disclosed in the Lord Patent No. 1,684,873. On this coating of water resistant adhesive is a 20 superficial coating 4 of a water soluble adhesive which may be of any suitable nature, such as the common animal, vegetable, or fish glues. In Fig. 3 this coating is shown covering only a part of the adhesive coating 3, but usually the entire 25 surface of the coating 3 will be covered by the coating 4.

Such a tape can be initially applied to the cartons in the ordinary taping and sealing machines. The tape usually is brought to these machines 30 in rolls, and the machine is equipped with means for unwinding the tape, applying a suitable length to a carton, moistening the gummed surface of the tape on its way to the carton, and cutting the tape at the proper intervals. Some parts of 35 such a mechanism are indicated diagrammatically in Fig. 1, the strip of tape unwound from the supply roll being shown at 2 and the gummed or adhesively coated surface of the tape being illustrated as running in contact with a moistening 40 roll 5. This tape is shown with its forward end applied to the carton blank 6 where it covers the joint 7 at the meeting edges of the sides of the carton. A proper length of tape will be cut off to substantially cover this joint.

45 The initial attachment of the tape to the carton is produced through the action of the water soluble coating 4 of gum or adhesive. Subsequently the layer of asphalt 3 or other water resistant adhesive must be softened sufficiently to 50 bond it securely to the carton. This result can be accomplished by hand or with the aid of a great variety of mechanisms. One convenient form of apparatus for performing this function is shown in Fig. 1. It consists of upper and lower 55 endless metal belts 10 and 11, respectively, supported on a suitable rolls with the lower reach of the upper belt running closely adjacent to but separated from the upper reach of the lower belt. The carton blank 6 is fed between these belts 60 where it will be gripped and carried along by them with the upper belt 10 bearing upon the reinforcing strip 2 which has just been applied to the carton. Located closely adjacent to this upper belt 10 are several electric heaters 12 which 65 serve to heat the belt to such a temperature that it will melt the adhesive 3 sufficiently to cause it to bond to the surface of the carton. In addition to softening the adhesive sufficiently to produce this result the belts also serve, due to the 70 way in which they are supported, to press the sealing tape firmly into contact with the carton while the adhesive is melted. A very secure union thus is produced between the backing strip 2 of the tape and the surface of the carton. The 75 conveying belts 10 and 11 should be made of

such a length that a suitable time interval will be afforded to fuse the water resistant adhesive 3 securely to the carton. A substantial length of time is required for this purpose and this fact has been an important practical objection to the 80 use of tapes coated with these adhesives in the commercial taping and sealing machines. The left-hand end, Fig. 1, of the conveyor belt 10 need not be heated, or may even be cooled so as to reduce the temperature of the adhesive 3 sufficiently to make it set or harden before the carton blank is discharged at the end of the conveyor. Or, the carton may be delivered to a second conveyor like the conveyor 10-11 but having 85 unheated belts which will perform this same function.

A very similar arrangement can also be used in connection with carton sealing machines for applying tape to the flaps of the carton to seal the carton. Usually, however, the backing for a 90 sealing tape consists simply of a strong paper.

In Fig. 2 a carton which has been set up, filled and sealed is shown at 6'. The reenforcing tape applied in the mechanism shown in Fig. 1 is illustrated in Fig. 2 at 2' and the sealing tapes 100 are shown at 2''.

I have demonstrated in practice that tapes of the character above described can be applied to cartons substantially as fast by this method as by the methods commonly used for applying 105 tapes coated with a water soluble adhesive. In addition, the thorough heating of the tape in the conveyor belts is of advantage in drying out the water used in making the initial temporary bond between the tape and the carton so that 110 when the cartons come out of the machine the reenforcing tape is thoroughly dried. This overcomes a disadvantage frequently experienced in using prior methods and in which the tapes come out of the sealing machine somewhat moist. The 115 carton flaps frequently are under considerable pressure at this time, and if the adhesive on the tape is still wet some slip frequently occurs between the tape and one or both of the carton flaps so that the carton will not be sealed tightly. In 120 some cases the flaps even fly open. In either event hand taping usually is resorted to later to overcome this difficulty.

In making the tape shown in Fig. 3 the asphalt or other water resistant adhesive may be applied 125 either in a melted condition or, more preferably, in the form of an emulsion. Emulsified asphalts are readily obtainable on the market and the adhesive composition disclosed in the patent above designated can also be emulsified. These 130 emulsions can be applied to the tape in the usual gumming machines and the necessity for installing an asphalt plant thus can be obviated.

If a cloth tape is used, it is preferable to fill 135 one side of the cloth with clay, talc or other suitable fillers in the manner disclosed in the Mc- Laurin Patent No. 1,759,124, the other side of the cloth to which the adhesive is to be applied being left unfilled. This filler is useful in preventing the adhesive from sweating through the 14 fabric when it is applied to the carton. A similar result can also be obtained by combining a strip of paper with the fabric and then applying the asphalt or other water resistant adhesive to the surface of the paper. When this process is 145 followed it is preferable to use a water resistant adhesive in performing the combining operation, although this is not absolutely necessary for all uses.

Instead of applying a superficial coating 4 of 15

water soluble adhesive to the underlying coat of water resistant adhesive, as in the arrangement above described, the two adhesives can be mixed and applied in a single coat. This is very easily 5 accomplished if the water resistant adhesive is used in the form of an emulsion. Any of the common glues, either fish or animal, or a mixture of the two, or vegetable gums which are soluble in water, can be mixed with the emulsion and this 10 mixture applied to the tape in a common gumming machine. I have obtained entirely satisfactory results with a mixture of 75% of water resistant adhesive with 25% of glue or other water soluble adhesive. A smaller percentage of 15 glue can, however, be used. A tape coated with this adhesive is shown in Fig. 4, the backing sheet of paper, cloth, or the like, being indicated at 14 and the coating of adhesive at 15. This tape can be handled in the ordinary taping and sealing 20 machines in the same manner as the tape shown in Fig. 3. In addition, it has the advantage of requiring a single coating operation only to apply the adhesive. For most purposes I consider this form of tape preferably to that previously 25 described.

It is also contemplated that instead of using the more common water soluble adhesives for the outer coating 4 on the inner coating 3 of the adhesive, this outer coating may consist of an 30 egg or blood albumen, or some equivalent substance which will give an initial tackiness sufficient to fasten the tape to the carton or other article of work and which will itself be rendered water resistant by the subsequent heating step 35 required to soften the coating of water resistant adhesive sufficiently to cause it to bond to the carton. This has the advantage of substantially eliminating water soluble constituents from the final adhesive composition which is relied upon 40 to bond the tape to the carton. At the same time it is open to the disadvantage of being more expensive and somewhat slower acting than the forms of the invention previously described.

Tapes of the character here disclosed have the 45 advantage not only of being highly resistant to the action of moisture and water, but, in addition, they are not likely to mold or to undergo the disintegration to which water soluble adhesives frequently are subject when exposed to severe 50 conditions. For these reasons they are particularly useful in connection with the packing of foods which must be stored in refrigerators or cold storage plants and they are useful in boxes of the set-up type as well as in cartons.

55 The method provided by this inventor makes it practical for the first time, so far as I am aware, to use tapes coated with water resistant meltable adhesives in reinforcing, staying and sealing machines at speeds satisfactory to the trade.

60 It will be understood that while I have explained the process or method provided by this invention in connection with certain apparatus, the use of this apparatus is not essential to the successful practice of the method or process, but that the method can be practiced by hand or with the aid of a great variety of mechanisms.

65 This application is a division of my pending application Serial No. 531,052, filed April 18, 1931. The claims made in this application are confined to the method of applying the tape or equivalent sheet material to cartons, packages, and the like, while all the claims in the parent application are directed to the tape and the 70 process of making it.

Having thus described my invention, what I desire to claim as new is:

1. That improvement in methods of applying sheet material to an article of work which consists in producing a temporary attachment of the sheet material to said article by means of a water soluble adhesive, and subsequently fusing a water resistant adhesive between said material and the work and thereby bonding the material securely to the work. 80

2. That improvement in methods of applying sheet material to an article of work which consists in interposing both a water soluble adhesive and a water resistant adhesive between said material and the work, moistening the water soluble adhesive prior to so interposing it, pressing the moistened adhesive surface against the work, and thereby producing an initial bond between said material and the work, subsequently melting said water resistant adhesive, and pressing said material against the work while the latter adhesive is melted and thereby producing a more secure union between said material and the work. 90

3. That improvement in methods of applying tapes to articles of work, such as cartons, which consists in producing an initial attachment of the tape to the article by means of a water soluble adhesive, and subsequently uniting said tape to the article by means of a water resistant adhesive interposed between said tape and the article. 100

4. That improvement in methods of applying tapes to articles of work, such as cartons, which consists in producing an initial attachment of the tape to the article by means of a water soluble adhesive, and subsequently uniting said tape to the article by means of a water resistant adhesive which is not substantially sticky at normal temperatures but which is adapted to become sticky when heated to temperatures substantially above normal. 115

5. That improvement in methods of applying tapes to articles of work, such as cartons, which consists in producing an initial attachment of the tape to the article by means of a water soluble adhesive, and subsequently uniting said tape to the article by fusing a waterproof adhesive between the tape and the article. 120

6. That improvement in methods of applying tapes to articles of work, such as cartons, which consists in producing a temporary adhesive union between the tape and article by means of a water soluble adhesive, and subsequently producing a more permanent union between said tape and article with a water resistant adhesive. 125

7. That improvement in methods of applying tapes to articles of work, such as cartons, which consists in interposing both a water soluble adhesive and a water resistant adhesive between the tape and the article, utilizing said water soluble adhesive to produce an initial union between the tape and said article and subsequently fusing said water resistant adhesive and thereby producing a more secure union between said tape and article. 130

8. That improvement in methods of applying a tape coated with a normally non-tacky water resistant adhesive to a carton or the like, which consists in producing a temporary attachment of the tape to the carton independently of said adhesive, subsequently softening said adhesive and pressing the tape against the carton while said adhesive is softened. 140

9. That improvement in methods of applying a tape coated with a normally non-tacky water resistant adhesive to a carton or the like, which consists in fastening said tape temporarily to the 150

carton without melting said adhesive, subsequently softening said adhesive sufficiently to make it sticky, and pressing the tape against the carton while the adhesive is so softened.

5 10. That improvement in methods of applying a tape coated with a normally non-tacky water resistant adhesive to a carton or the like, which

consists in producing a temporary attachment of the tape to the carton with a water soluble adhesive, subsequently melting said adhesive, and pressing the tape against the carton while the adhesive is so melted.
